UNITED STATES PATENT OFFICE

123,199

DESIGN FOR A CURTAIN STRETCHER

Walter W. Block, Kenosha, Wis.

Application July 15, 1940, Serial No. 93,668

Term of patent 14 years

To all whom it may concern:

Be it known that I, Walter W. Block, a citizen of the United States, residing at Kenosha, in the county of Kenosha and State of Wisconsin, have invented a new, original, and ornamental Design for a Curtain Stretcher, of which the following is a specification, reference being made to the accompanying drawing, forming a part thereof.

Fig. 1 is a perspective view of a curtain stretcher showing my new design; and

Fig. 2 is a rear perspective view thereof.

The present application is a continuation-in-part of an application for design patent filed by me on or about January 24, 1940, Serial No. D-89,681.

I claim:

The ornamental design for a curtain stretcher, as shown.

WALTER W. BLOCK.
